CLAIM

The ornamental design for a wireless charger, as shown and described.

DESCRIPTION

FIG. 1 is a front, right and bottom perspective view of a wireless charger, showing our new design;

FIG. 2 is a rear, left and bottom perspective thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 of the wireless charger in FIG. 1;

FIG. 10 is an enlarged view of portion 10 of the wireless charger in FIG. 2;

FIG. 11 is an enlarged view of portion 11 of the wireless charger in FIG. 3; and,

FIG. 12 is an enlarged view of portion 12 of the wireless charger in FIG. 4.

The broken lines shown in the drawings illustrate portions of the wireless charger that form no part of the claimed design. The dot-dash broken lines depict the boundaries of the enlargements that form no part of the claimed design.

1 Claim, 12 Drawing Sheets
